E. R. MITCHELL

DOOR RETAINER

Filed June 25, 1925

Inventor:
Ernest R. Mitchell,
by his Attorneys:
Howson & Howson

UNITED STATES PATENT OFFICE.

ERNEST R. MITCHELL, OF PHILADELPHIA, PENNSYLVANIA, ASSIGNEE TO MITCHELL
SPECIALTY COMPANY, OF PHILADELPHIA, PENNSYLVANIA, A CORPORATION OF
PENNSYLVANIA.

DOOR RETAINER.

Application filed June 25, 1925. Serial No. 39,538.

This application relates to a door retainer of the type wherein a lug carried by the door of an automobile is engaged between and held by metallic strips or guards which cover the adjacent opposed surfaces of two blocks of rubber or other resilient material. My improved construction embodies some of the features discussed in and covered by my copending application for door retainer, 10 Ser. No. 635,065, filed April 27, 1923.

One of the objects of the present invention is to provide an improved means for holding the resilient blocks forming a part of the retainer, together with improved details of the said blocks. A further object of the invention is to provide means for securing the door retainer in place on the door frame or post. Still further objects of the invention will be apparent from the following specification and claims.

In the accompanying drawing I have shown different embodiments of the invention but it will be understood that the drawing is for illustrative purposes only and that various changes and further substitutions may be made within the scope of the claims without departing from the spirit of the invention.

Of the drawing:

Fig. 1 is an elevational view, partly in section, of a part of a door frame carrying a door retainer embodying the invention.

Fig. 2 is an edge view of the parts shown in Fig. 1, this view being partly in section along the line 2—2 of Fig. 1.

Fig. 3 is a sectional view taken along the line 3—3 of Fig. 1.

Figs. 4 and 5 are elevational and edge views respectively of the retaining lug adapted to be secured to the door.

Fig. 6 is a detail perspective view showing an alternate construction for the resilient block elements.

Fig. 7 is a detail perspective view showing another alternate construction of the blocks and guards.

Figs. 8, 9 and 10 are views similar respectively to Figs. 1, 2 and 3 but showing an alternate form of the invention, Fig. 9 is partly in section along the line 9—9 of Fig. 8, and Fig. 10 is in section along the line 10—10 of Fig. 8.

Referring particularly to Figs. 1, 2 and 3 of the drawing, 1 and 2 represent respectively two opposed blocks formed of rubber

or other suitable resilient material. The blocks may be formed separately or as parts of a single unitary block member. In Fig. 1, I have shown them as being separate, but in either case they are spaced apart and are so shaped and proportioned as to be adapted to be located in a recess formed in a door frame or post. The door frame may be of either wood or metal. Preferably the corners of the blocks are rounded at 3—3 so that the corners of the recess can be similarly rounded. When the door frame is formed of wood the rounding of the corners of the recess is an important factor as this permits the recess to be much more cheaply machined. With a steel door frame the recess can be pressed inward and shaped as required.

Carried by the blocks 1 and 2 are two guards 4 and 5 respectively engaging the adjacent opposed surfaces of the blocks. These guards are preferably so supported by the blocks that their ends are out of contact with any other part of the door retainer or other structure, so that they are free to move upward, or downward, or laterally in directions parallel to the face of the door frame as permitted by the resiliency of the blocks. It will be understood that a retaining lug carried by the door, and hereinafter described, is adapted to enter between the guards 4 and 5. The door is thus guided into proper position and the construction described permits the guards to be bodily moved by the retaining lug vertically or laterally when the car is being driven over rough roads, thus eliminating all rattles, squeaks and other unnecessary noises. Preferably in addition to moving vertically or laterally as described, the guards are made narrower than the blocks, as clearly shown in Fig. 2, so that they are also movable to a slight extent transversely. This feature is also of considerable advantage in eliminating noises.

There can be variation in the details of the guards 4 and 5, but I ordinarily prefer to make them as parts of a single U-shaped member which fits between the blocks 1 and 2. This U-shaped guard member lies in and fits the space 6 between the blocks 1 and 2. The U-shaped member is bowed out at 7 to fit a corresponding enlargement of the notch 6 and the ends of the member are flared at 8—8. The U-shaped member is thus held

2
by the block member against endwise movements and it will be observed that the bowed section 7 and the flared ends 8-8 are entirely disengaged from any parts of the retainer other than said block member.

A plate 9 is provided which is adapted to entirely cover the blocks and the guards and also to entirely cover and close the recess in the frame. The plate is large enough to extend somewhat beyond the edges of the recess so as to provide a good finish. Preferably this plate is flanged over at 10 and 11 to conform to the contour of the door frame. It is provided with an opening 12 which permits the retaining lug to enter between the resilient blocks and the guards.

In accordance with my invention I provide holes in the resilient blocks 1 and 2 into which extend suitable means for holding the said blocks and the said plate 9 against relative bodily movement in directions parallel to the plane of the plate. As to the details of these holding means, there can be variation but I prefer to so form the holding means that they will not only prevent relative bodily movement in directions parallel to the plane of the plate, but will also serve to permanently secure the block elements to the plate. In Figs. 1 to 3 I have shown rivets 13 which extend through holes in the plate and also through holes in the block elements, these rivets being flanged over at 14-14 so as to secure the block elements in place. Preferably I also utilize the rivets 13-13 as a means for holding the entire retainer in place on the door frame. To this end the said rivets are made hollow in the form of bushings so that retaining screws 15 can extend through these bushings into the material of the door frame. It will be noted that the rivets or bushings 13-13 abut against the bottom of the recess, thus serving to resist the pull of the screws and to prevent any tendency for the resilient blocks to be compressed or deformed.

In Figs. 4 and 5 I have shown one type of retaining lug which may be used but it will be understood that my present invention does not particularly relate to the retaining lug and that the construction of this may be widely varied. As shown, this retaining lug comprises a single piece of sheet metal 16 which has the lug proper 17 formed integrally with it by stamping. Counter-punched screw holes are provided at 18 for securing the lug to the door. It will be understood that the lug is of such a size and is so located on the door that when the door is shut the lug proper will enter between the guards 4 and 5 of the retaining means and slightly separate them so as to compress the blocks 1 and 2.

65 In Fig. 6 I have shown an alternate con-

struction, wherein the resilient blocks are formed as parts of a single unitary block member which is provided with a notch 19. This notch divides the block member to form the aforesaid blocks 1^a and 2^a, leaving a narrow connecting strip 20 between them.

In Fig. 7 I have shown an alternate construction of both the blocks and the guards. Two separate blocks, such as 1^b, are provided, and also separate guards, such as 4^b. Each guard is curved inward and backward at its ends to engage similarly curved surfaces on the block. Each guard is thus directly secured to the corresponding block and has interlocking engagement therewith, and the block and the guard can be handled as a unit. It will be noted that in this construction the ends of each guard are so formed and located that, when assembled, they are out of contact with any other part of the door retainer or other structure. Preferably also the guards are narrower than the blocks so as to have no contact at their edges with any other parts. This construction, therefore, has all of the advantages already set forth in connection with the construction first described.

In Figs. 8, 9 and 10 I have shown another alternate form of the invention wherein an enclosing box structure 21 is provided for the resilient blocks. This box structure is shaped to conform to the outline of the blocks and the entire construction is such that this box structure can be added or omitted without changing the construction or design of any of the other parts of the device except the rivets 13-13. As shown this box structure 21 is made of sheet metal and it is provided with holes adapted to register with the holes in the plate 9 and in the blocks. Rivets 13^a-13^a extend through the holes in all three of these parts and are flanged over to hold them in fixed relation. It will be understood that these rivets are hollow as already described to receive the screws 15-15 which hold the entire door retainer in place.

It will be noted that with any of the constructions shown and described the entire retainer can be completely assembled as a unit, this being highly advantageous in handling and shipping and also in the fitting of the retainer to the door frame.

What I claim is:

1. In a door retainer, two opposed resilient blocks adapted to lie in a recess in a door frame, metallic guards carried by the two blocks and adapted to receive a door retaining lug between them, a plate extending over the blocks to cover the recess in the frame and having an opening therein to permit the retaining lug to engage the said metallic guards, a box cooperating with the plate to enclose the blocks and the guards, and means extending through holes in the

blocks for holding the said blocks, the said plate and the said box against relative bodily movement in directions parallel to the plane of the plate.

- 5 2. In a door retainer, two opposed resilient blocks adapted to lie in a recess in a door frame, metallic guards carried by the two blocks and adapted to receive a door retaining lug between them, a plate extending 10 over the blocks to cover the recess in the frame and having an opening therein to permit the retaining lug to engage the said metallic guards, a box cooperating with the plate to enclose the blocks and the guards, 15 and means extending through holes in the blocks, positively engaging both the box and the plate for securing the said box and the said blocks to the plate.
3. In a door retainer, two opposed resilient blocks adapted to lie in a recess in a door frame, metallic guards carried by the two blocks and adapted to receive a door retaining lug between them, a plate extending 20 over the blocks to cover the recess in the frame and having an opening therein to permit the retaining lug to engage the said metallic guards, a box cooperating with the plate to enclose the blocks and the guards, 25 and members extending through holes in the blocks and positively engaging the box and the plate for securing the said box and the said blocks to the plate, the said members being hollow and adapted to receive screws for holding the door retainer in place.

- 35 4. In a door retainer, two opposed resilient blocks adapted to lie in a recess in a door frame, a plate extending over the blocks to cover the recess in the frame and having an opening therein to permit a retaining 40 lug to enter between the blocks, metallic guards adapted to receive the said door retaining lug between them, the said guards being carried solely by the blocks out of contact with any other parts so as to be bodily 45 movable by the lug in any direction as permitted by the resiliency of the blocks, and means carried by the plate and extending through holes in the block and positively engaging the said blocks for securing them 50 to the plate.

5. In a door retainer, two opposed resilient blocks adapted to lie in a recess in a door frame, a plate extending over the blocks

to cover the recess in the frame and having an opening therein to permit a retaining lug 55 to enter between the blocks, metallic guards adapted to receive the said door retaining lug between them, the said guards being carried solely by the blocks with their ends out of contact with any other parts so as to be bodily movable by the lug in any direction 60 parallel with the plate as permitted by the resiliency of the blocks, a box cooperating with the plate to enclose the blocks and the guards, and members extending 65 through holes in and positively engaging at their ends with the said box and the said plate for securing the said box and the blocks to the plate.

6. In a door retainer, a one-piece resilient 70 block member adapted to lie in a recess in a door frame, the said block member having a notch therein forming two opposed blocks, metallic guards located in the notch and engaging respectively with the two 75 blocks of the block member and adapted to receive a door retaining lug between them, a plate extending over the block member to cover the recess in the frame and having an opening therein to permit the retaining lug 80 to engage the said metallic guards, and headed rivet members extending through holes in the two blocks of the block member and holes formed in said plate for positively securing the former to the latter. 85

7. In a door retainer, a one-piece resilient block member adapted to lie in a recess in a door frame, the said block member having a notch therein forming two opposed blocks, metallic guards located in the notch 90 and engaging respectively with the two blocks of the block member and adapted to receive a door retaining lug between them, a plate extending over the block member to cover the recess in the frame and having an 95 opening therein to permit the retaining lug to engage the said metallic guards, a box cooperating with the plate to enclose the block member and the guards, and members extending through holes in the two blocks of 100 the block member and positively engaging at their ends with the said box and the said plate for securing the box and the block to the plate.

ERNEST R. MITCHELL.
